US00D811913S

(12) **United States Design Patent** (10) **Patent No.:** **US D811,913 S**
(45) **Date of Patent:** **** Mar. 6, 2018**

(54) **DIAGNOSTIC ANALYZERS**

(71) Applicant: **Abbott Laboratories**, Abbott Park, IL (US)

(72) Inventors: **Christina A. Barton**, Irving, TX (US); **Vladlena Belozerova**, Philadelphia, PA (US); **Ami Marie Verhalen**, Sun Prairie, WI (US); **Jesse Charles Darley**, Madison, WI (US); **Sherry Sue Eckholm**, Sun Prairie, WI (US)

(73) Assignee: **ABBOTT LABORATORIES**, Abbott Park, IL (US)

(**) Term: **15 Years**

(21) Appl. No.: **29/587,978**

(22) Filed: **Dec. 16, 2016**

(57) **CLAIM**

The ornamental design for "diagnostic analyzers," as shown and described.

DESCRIPTION

FIG. 1 is a front left perspective view of diagnostic analyzers.

FIG. 2 is a front view of the diagnostic analyzers of FIG. 1.

FIG. 3 is a rear view of the diagnostic analyzers of FIG. 1.

FIG. 4 is a right side view of the diagnostic analyzers of FIG. 1.

FIG. 5 is a left side view of the diagnostic analyzers of FIG. 1.

FIG. 6 is a top view of the diagnostic analyzers of FIG. 1.

FIG. 7 is a bottom view of the diagnostic analyzers of FIG. 1.

FIG. 8 is a front left perspective view of diagnostic analyzers.

FIG. 9 is a front view of the diagnostic analyzers of FIG. 8.

FIG. 10 is a rear view of the diagnostic analyzers of FIG. 8.

FIG. 11 is a right side view of the diagnostic analyzers of FIG. 8.

FIG. 12 is a left side view of the diagnostic analyzers of FIG. 8.

FIG. 13 is a top view of the diagnostic analyzers of FIG. 8; and,

FIG. 14 is a bottom view of the diagnostic analyzers of FIG. 8.

The features shown in broken lines form no part of the claimed design.
